UNITED STATES PATENT OFFICE.

CARL J. SCHMITT AND KARL R. SCHUNDLER, OF BROOKLYN, NEW YORK.

KNOCKDOWN DOLL-HOUSE.

1,333,455.

Specification of Letters Patent.

Patented Mar. 9, 1920.

Application filed April 18, 1919. Serial No. 290,972.

To all whom it may concern:

Be it known that we, CARL J. SCHMITT, a citizen of the United States, and a resident of the city of New York, borough of Brooklyn, in the county of Kings and State of New York, and KARL ROBERT SCHUNDLER, a citizen of Germany, and a resident of the city of New York, borough of Brooklyn, in the county of Kings and State of New York, have invented a new and Improved Knockdown Doll-House, of which the following is a full, clear, and exact description.

The invention relates to toys and its object is to provide a new and improved knockdown doll house formed of a plurality of units representing various rooms in a dwelling, such as a kitchen, sitting room and bedroom, for instance. Another object is to permit a child to readily assemble the various elements of the units without the aid of a grown-up person. Another object is to enable a child to completely close the doll house by the use of removable front walls. Another object is to provide a simple or a more elaborate doll house, the simple doll house being without a roof and front walls while the more elaborate doll house is provided with both.

With these and other objects in view, the invention consists of certain novel features of construction, as hereinafter shown and described, and then specifically pointed out in the claims.

A practical embodiment of the invention is represented in the accompanying drawings forming a part of this specification, in which similar characters of reference indicate corresponding parts in all the views.

Figure 1 is a perspective view of the improved knockdown doll house with one of the front walls in partly open position;

Fig. 2 is a sectional plan view of the improved doll house;

Fig. 3 is a rear elevation of the same;

Fig. 4 is a cross section of the same along one of the partitions dividing one room from the other;

Fig. 5 is a rear elevation of one of the back walls;

Fig. 6 is an enlarged cross section of one of the front walls, portions of the floor and roof and the coping and sill;

Fig. 7 is a perspective view of a portion of the sill;

Fig. 8 is an enlarged inverted plan view

of portions of adjacent room units with parts in section showing the dowel pin connection between the floors of adjacent units;

Fig. 9 is a rear face view of one end of a 60 sill; and

Fig. 10 is an end view of the same.

The knockdown doll house in its general construction comprises room units, of which the three units 10, 11 and 12 are shown, for 65 instance, in Figs. 1, 2 and 3, the said units being detachably connected with each other. Each unit is formed of elements of wood, pasteboard or other sheet material, and connected with each other by exceedingly simple means to allow convenient assembling or disassembling of the elements by a child without the aid of a grown-up person. The units 10, 11 and 12 shown in the drawings are decorated interiorly to represent a 70 kitchen, a living room and a bedroom, and the said units are intended to be furnished accordingly to suit the taste and means of the owner.

Each of the room units 10, 11 and 12 80 comprises a floor 13 and a back wall 14, and the room units 10 and 12 have end walls 15 and transverse partitions or end walls 16 dividing the units into different rooms. The floors 13 of the several units are detachably fastened together at adjacent sides by 85 dowel pin 20 to serve to hold the floors on the same level and to prevent lateral displacement of the floors. Adjacent floors 13 are detachably connected with each other at 90 their upper surfaces by suitable fastening devices such as hooks 21 and pins 22, of which the hook is pivoted on one floor and the pin is attached to the other floor, as plainly shown in Fig. 2. It is understood 95 that by this arrangement the floors are held properly joined together so as to present a continuous unbroken floor surface throughout the several units. The back walls 14 are connected with each other by suitable 100 fastening devices extending across the joints of the said back walls (see Fig. 3) and each fastening device is preferably in the form of a hook 23 and a pin 24, of which the hook 23 is fulcrumed on the rear face of 105 one back wall and adapted to hook onto a pin 24 held on the rear face of the adjacent back wall. Dowels 27 (see Fig. 2) are used for detachably connecting the back walls 14 with each other.

The end walls 15 and the transverse partitions 16 are provided at their bottoms with

apertured tenons 25 extending through openings formed in the floors 13, and into the openings for the said tenons 25 are pushed pins 26 engaging the under sides 5 of the floors 13 to hold the end walls 15 and the partitions 16 in vertical position on the connected floors. The tenons 25 of the end walls 15 engage openings formed adjacent the outer sides of the floors 13 of the units 10 and 12 while the openings for the tenons 25 of the partitions 16 are halved in the adjacent sides of the floors 13 of the units 10, 11 and 11, 12, as will be readily understood by reference to Fig. 8. The rear edges of 15 the end walls 15 and the partitions 16 are provided with similar apertured tenons 30 extending through openings in the back walls 14 and the said tenons are engaged by pins 31 adapted to rest against the rear 20 face of the back walls 14 thus securely fastening the rear walls in position on the end walls 15 and the partitions 16. It is understood that the tenons 30 for the end walls 15 extend through apertures 32 formed near the 25 outer sides of the back walls 14 of the units 10 and 12, while the tenons 30 for the partitions 16 pass through openings 33 halved in the adjacent side edges of the back walls 14 for the units 10, 11 and 11, 12 (see Fig. 30 5). It will be noticed that the partitions 16 extend over the joints between adjacent floors and the joints between the adjacent back walls 14 thus forming an additional means for securely holding the elements of 35 the several units in assembled position. The end walls 15 are preferably provided with window openings 40 and similar window openings 41 are arranged in the back walls 14. The partitions 16 are preferably provided with door openings 42 to connect the 40 units interiorly with each other.

The construction so far set forth provides for a doll house of simple construction, that is, one without a roof or front walls, and 45 for more elaborate and expensive doll houses use is made of a roof 50, a front wall 51, a coping 52 and a front sill 53 for each unit. The roofs 50 for the several units rest on the top of the back walls 14, the end walls 50 15 and the partitions 16, and the adjacent sides of the roofs 50 are detachably fastened together by suitable fastening devices such as hooks 54 and pins 55, of which the hooks 54 are fulcrumed on one roof and the pins 55 are affixed to the other roof, as plainly shown in Fig. 1.

The front wall 51 is mounted to slide side- 60 wise in suitable guideways 60 and 61, of which the guideway 60 is formed in the under side of the coping 52 and the guideway 51 is formed in the top of the front sill 53. The coping 52 is provided at its rear face with a lengthwise extending groove 62 into which is glued the front edge of the 65 corresponding roof 50, as plainly shown in

Fig. 6. The front sill 53 is provided at its rear face with a lengthwise extending groove 63 detachably fitting on to the front edge of the corresponding floor 13 (see Fig. 6). The rear faces of the sills 53 for the 70 units 10 and 12 are provided near their outer ends with notches 65 fitting onto the front edges of the end walls 15, and the inner ends of the sills 53 for the units 10 and 12 and both ends of the sill 53 for the unit 75 11 are provided with registering half notches 66 adapted to fit the front edges of the partitions 16. The adjacent ends of the sills 53 are provided with dowel pins 70 and 71 engaging corresponding recesses 72, 73 80 formed in the adjacent ends of the sills 53, as will be readily understood by reference to Fig. 9. The inner faces of the coping 52 are provided with half notches (not shown) similar to the notches 65 and 66 for engaging 85 the front edges of the end walls 15 and the partitions 16.

The front walls 51 for the units 10 and 12 are preferably provided with imitation windows 80 while the front wall 51 for the 90 middle unit 11 is preferably provided with an imitation door 81, as plainly shown in Figs. 1 and 2. The front wall 51 for the middle section 11 is preferably provided at its sides with vertical battens 85 95 adapted to project over the adjacent inner sides of the front walls 51 for the units 10 and 12 whenever said front walls are in closed position, as plainly shown in Fig. 2. The outer sides of the front walls 51 for the 100 end units 10 and 12 are provided with battens 86 to give a proper finish to the front walls and to form a handle for conveniently sliding the front walls in or out of position.

From the foregoing it will be seen that 105 the several units are detachably connected with each other to provide a single structure, and the several units can be readily disconnected one from the other and the elements of each unit can be conveniently detached one from the other to allow of superimposing the elements and packing the same in a suitable box or boxes for storage or 110 shipping purposes.

It is understood that in order to unfasten 115 the several parts it is only necessary to disengage the various hooks 21, 23 and 54 from their pins 22, 24 and 55 and to remove the locking pins 26 and 31 to permit of readily disconnecting the various elements. It will 120 further be noticed that exceedingly simple fastening and connecting means are employed to enable a child to readily assemble and fasten the elements together without the aid of a grown-up person.

Having thus described our invention, we claim as new and desire to secure by Letters Patent:—

1. A doll house, comprising at least two room units and a transverse partition be- 130

tween adjacent units, each unit having a floor, a back wall, an end wall, a roof, a coping, a sill and a front wall slidably mounted on the said coping and sill, and fastening means detachably fastening the said elements of the units and the partition together.

2. A doll house, comprising at least two room units and a partition common to both units, each unit having a floor, a back wall, an end wall and a transverse partition between the units and covering the joints of adjacent floors and back walls, fastening means fastening the floors detachably together, fastening means fastening the back walls detachably with each other, fastening means fastening the end wall detachably to the floors and detachably to the back walls, and fastening means fastening the partition detachably to the adjacent floors and the adjacent back walls.

3. A doll house, comprising at least two room units and a partition common to both units, each unit having a floor, a back wall and an end wall, the said partition extending transversely between the units and covering the floor and back wall joints, the adjacent ends of the floors having dowel pin connections, the rear edges and bottoms of the said end walls and partition having apertured tenons and the floors and back walls having openings for receiving the tenons, and locking pins extending through the tenons and resting against the floors and rear walls.

4. A doll house, comprising at least two

room units and a partition common to adjacent units, each unit having a floor, a back wall, an end wall, a roof, a sill held detachably on the front edge of the floor, a coping held on the front edge of the roof, and front walls, one for each unit and slidably on the said coping and sill.

5. A doll house, comprising a floor, end walls detachably fastened to the said floor, a back wall detachably fastened to the said floor and end walls, a roof resting on the said end walls and the back wall, a coping connected with the front edge of the said roof and provided at its under side with a guideway, a sill detachably connected with the front edge of the said floor and provided at the top with a guideway, and a front wall slidably connected with the said coping and sill.

6. A doll house, comprising a plurality of floor sections, and walls detachably secured to the end floor sections, a plurality of back wall sections detachably secured to the floor sections and end walls, a roof resting on the end walls and the back wall sections, partitions secured to the floor and back wall sections and covering the joints of the said sections, a coping secured to the front edge of the roof and having a guideway on its underside, a sill secured to the front edge of the floor and provided in its top with a guideway, and a plurality of front wall sections slidable in the guideways of the coping and sill.

CARL J. SCHMITT.

KARL R. SCHUNDLER.
